UNITED STATES PATENT OFFICE.

ELMORE F. BOUBEL, OF DENVER, COLORADO.

DESIGN FOR A CURTAIN.

No. 37,909.

Specification for Design.

Patented March 20, 1906.

Application filed January 8, 1906. Serial No. 295,187. Term of patent 14 years.

To all whom it may concern:

Be it known that I, ELMORE F. BOUBEL, a citizen of the United States, residing in the city and county of Denver and State of Colorado, have invented a new, original and ornamental Design for a Curtain, reference being had to the accompanying drawing, which forms a part of this specification.

This invention relates to a new, original, and ornamental design for a curtain, the said

design being illustrated in the accompanying drawing, which is an elevation of a curtain, showing my new design.

What I claim is—

The ornamental design for a curtain as shown.

ELMORE F. BOUBEL.
